US0D1046583S

(12) **United States Design Patent** (10) Patent No.: **US D1,046,583 S**
Gallagher et al. (45) Date of Patent: ** Oct. 15, 2024

(54) **CONCRETE VIBRATOR**(71) Applicant: **MILWAUKEE ELECTRIC TOOL CORPORATION**, Brookfield, WI (US)(72) Inventors: **Patrick D. Gallagher**, Oak Creek, WI (US); **Travis J. Dubnicka**, Menomonee Falls, WI (US); **Mitchell Carlson**, Lisbon, WI (US); **Paul W. Eiche**, Oconomowoc, WI (US); **Eric C. Onsager**, Milwaukee, WI (US); **Wesley S. Bassindale**, Wauwatosa, WI (US); **Matthew Leidel**, Wind Lake, WI (US); **Erick Moreno Flores**, Milwaukee, WI (US)(73) Assignee: **MILWAUKEE ELECTRIC TOOL CORPORATION**, Brookfield, WI (US)(***) Term: **15 Years**(21) Appl. No.: **29/845,818**(22) Filed: **Jul. 11, 2022**(51) LOC (14) Cl. ..... **08-05**(52) U.S. Cl. USPC ..... **D8/61**(58) **Field of Classification Search**USPC D13/112; D15/147; D8/61, 67-69
CPC E04G 21/08; E04G 21/063; E04G 21/066;

(57) CLAIM

The ornamental design for a concrete vibrator as shown and described.

DESCRIPTION

FIG. 1 is a first perspective view of a concrete vibrator in accordance with an embodiment of the present invention.

FIG. 2 is a second perspective view of the concrete vibrator of FIG. 1.

FIG. 3 is a left-side view of the concrete vibrator of FIG. 1.

FIG. 4 is a right-side view of the concrete vibrator of FIG. 1.

FIG. 5 is a front view of the concrete vibrator of FIG. 1.

FIG. 6 is a rear view of the concrete vibrator of FIG. 1.

FIG. 7 is a top view of the concrete vibrator of FIG. 1.

FIG. 8 is a bottom view of the concrete vibrator of FIG. 1.

FIG. 9 is a first perspective view of a concrete vibrator in accordance with another embodiment of the present invention.

FIG. 10 is a second perspective view of the concrete vibrator of FIG. 9.

FIG. 11 is a left-side view of the concrete vibrator of FIG. 9.

FIG. 12 is a right-side view of the concrete vibrator of FIG. 9.

FIG. 13 is a front view of the concrete vibrator of FIG. 9.

FIG. 14 is a rear view of the concrete vibrator of FIG. 9.

FIG. 15 is a top view of the concrete vibrator of FIG. 9; and,

FIG. 16 is a bottom view of the concrete vibrator of FIG. 9.

The portions of the concrete vibrator shown in broken lines are included for the purpose of illustrating environment and form no part of the claimed design.
